United States Patent [19]

Leib

[11] Patent Number: Des. 318,578

[45] Date of Patent:  Jul. 30, 1991

[54] PLURAL SEATING UNIT

[76] Inventor: Roger K. Leib, 1064 Crescent Heights, Los Angeles, Calif. 90035

[] Term: 14 Years

[21] Appl. No.: 889,188

[22] Filed: Jul. 24, 1986

Related U.S. Application Data

[62] Division of Ser. No. 833,977, Feb. 26, 1986, abandoned.

[52] U.S. Cl. D6/381

[58] Field of Search 297/232, 248, 422, 460; D6/373, 380, 381, 379
